Primary Examiner — T. Chase Nelson*Assistant Examiner* — Mark Cavanna(74) *Attorney, Agent, or Firm* — Knobbe Martens Olson & Bear LLP**CLAIM**

The ornamental design for an inversion plate sleeve, as shown and described.

DESCRIPTION

FIG. 1 is a perspective view of an inversion plate sleeve in accordance with the present invention.

FIG. 2 is a top view of the inversion plate sleeve of FIG. 1.

FIG. 3 is a bottom view of the inversion plate sleeve of FIG. 1.

FIG. 4 is a front view of the inversion plate sleeve of FIG. 1. FIG. 5 is a back view of the inversion plate sleeve of FIG. 1. FIG. 6 is a left end view of the inversion plate sleeve of FIG. 1.

FIG. 7 is a right end view of the inversion plate sleeve of FIG. 1.

FIG. 8 is an exploded view of the inversion plate sleeve of FIG. 1 in combination with an inversion plate and a receiving plate; and,

FIG. 9 is an perspective view of the inversion plate sleeve of FIG. 1 in combination with an inversion plate and a receiving plate.

The broken lines are included for the purpose of illustrating unclaimed portions of the inversion plate sleeve as well as unclaimed environmental structure in the form of the inversion plate and receiving plate. The broken lines in the drawings form no part of the claimed design.
